UNITED STATES PATENT OFFICE

JOSEPH R. CRISP, OF WEST ASHEVILLE, NORTH CAROLINA

REGISTERING INCLINOMETER

Application filed July 9, 1930. Serial No. 466,845.

This invention relates to registering inclinometers, and has for an object the production of an inclinometer of improved type which shall be adjustable to any inclination and retain the registry of that inclination.

A further object of the invention is the production of an inclinometer having, in its normal adjustment, spirit level glasses of substantially the usual and ordinary type, which will register both level and plumb in the usual manner.

A further object of the invention is to provide an inclinometer in which the spirit levels, fixed at an angle of 90°, are carried by a movable part, which moves under manual control to some inclination other than level and plumb, and remains in such assumed position until manually returned to normal, or to another inclination.

A further object of the invention is to provide the moving part with a table of figures which shall coact with a pointer, so that the inclination assumed by said moving part shall indicate, from the chart reading, the use to be made from the registered inclination.

A further object of the invention is to provide the necessary mechanical parts to carry forward the above objects.

With these and other objects in view the invention comprises certain novel parts, combinations, elements, mechanical and functional units, together with mechanical and functional equivalents thereof as will be hereinafter more fully described and claimed.

In the drawings,

Fig. 1 is a view of the invention in side elevation associated with a level stock shown in fragment.

Fig. 2 is a view of the operating parts of the inclinometer in side elevation, with the outer protecting plate and glass removed.

Fig. 3 is a transverse sectional view taken on line 3—3 of Fig. 1.

Fig. 4 is a view in side elevation of the outer protecting plate.

Fig. 5 is a view in side elevation of the band or frame which is mounted within the stock and carries all of the operative parts.

Fig. 6 is a view in side elevation of the

movable part, which will be hereinafter referred to as the disk.

Fig. 7 is an enlarged detail view of the manual control.

Like characters of reference indicate corresponding parts throughout the several views.

The improved inclinometer which forms the subject matter of the application, comprises a stock, similar to the usual and ordinary spirit level stock, and serving every function of such a spirit level in the manner to be herein more fully set forth.

The stock 10, is provided at some position within its length, preferably centrally, with a cut out portion extending entirely through the stock, and therefore, opening upon both lateral sides. Within this cut out a frame 11 is positioned, said frame 11 being in the form of a semi-circle with a diametrical bar 12. The bar 12 carries midway of its ends a bearing block 13, and the frame is held in position within the stock by a screw 14, extending through the adjacent part of the stock and engaging the bearing block 13. Journalled within the bearing block 13, by a pintel 15, is a clip 16, rigidly attached to the disk 17, all oscillating upon the pintel 15. Oscillation is imparted to the parts manually by providing the clip 16, with an arcuate rack 18, engaged by a sliding rack 19, which extends parallel with the bar 12, and outwardly through the frame 11, provided with a screw-threaded portion 20, with a knurled nut 21, mounted to rotate in the frame 11, but held against longitudinal movement by the circular channel 22.

The disk 17 is provided along the edge which is normally parallel with the bar 12, with a spirit level glass 23, with another fixed to the disk at an angle of 90° as indicated at 24, spaces 25 and 26 being provided to receive said glasses and make them visible from both sides. A screw 27, forms a stop for the disk, and is manually adjustable to stop the disk at the exact position so that the glasses 23 and 24, shall indicate level and plumb, when the disk is in contact with the adjusting screw 27, which screw also supplements the

screw 14, in maintaining the frame in position.

The frame carries a pointer 28, which indicates upon the disk 17 certain graduations 29, upon the disk, having proper leads to a chart 30. The chart as shown indicates generally a framing chart, but it is to be understood that the invention is in no way limited to any specific chart, or to any chart at all, and the chart is only indicated to suggest a utility for the device.

The disk 17 is provided with an edge 31 which will serve as a stop to limit the movement of the disk to an amplitude of 45° from normal.

The whole working part is covered and protected by plates 32 inset into the stock and provided with slots 33 for the knurled nut 21 so that the said nut shall be accessible from without the plates. Between each plate and the edge of the frame 11 is positioned a sheet of a transparent medium 33, which may be glass or some less fragile material.

In operation with the parts assembled as shown at Fig. 1, the device serves in all respects as a level, as usually employed by mechanics. When, however, it is desirable to ascertain the inclination of a given body the nut 21 is manipulated until one or the other of the level glasses indicates level in the usual manner, and the inclination may then be read by the position of the graduations relative to the pointer 28. If the requirement is framing, for example, the exact framing cut may be ascertained from the chart. If some other chart is employed for some other purpose, the utility will be at once apparent.

I claim:

1. A registering inclinometer comprising a stock, means in said stock having a semicircular opening therein with its straight side parallel to one side of said stock, a circular sector element pivoted in said means at the center of said semicircular opening, means located in the plane of said stock and parallel to one side thereof for manually adjusting the position of said sector, and a pair of leveling units mounted on said sector at right angles to each other.
2. A registering inclinometer comprising a stock, means in said stock having a semicircular opening therein with its straight side parallel to one side of said stock, a circular sector element pivoted in said means at the center of said semicircular opening, means located in the plane of said stock and parallel to one side thereof for manually adjusting the position of said sector, and a pair of leveling units mounted on said sector at right angles to each other, said sector having a table of graduations thereon, and a pointer carried by said stock and cooperating with the said graduations.
3. A registering inclinometer comprising a stock, an open semicircular frame mounted

therein with its straight side parallel to one side edge of said stock, a circular sector pivoted at the center of said frame to move in the plane of said stock, said sector having a series of graduations thereon, a pointer mounted on said frame for cooperation with said graduations, a pair of leveling units carried by said sector and mounted at right angles to each other and means mounted in said frame and within the plane of the stock for adjusting the position of the sector with respect to the stock.

In testimony whereof I affix my signature.

JOSEPH R. CRISP.
